[57] CLAIM

The ornamental design for a solitaire playing board, as shown and described.

DESCRIPTION

FIG. 1 is a perspective view of a solitaire playing board showing my new design;

FIG. 2 is a top plan view thereof, the bottom being plain and unornamented;

FIG. 3 is an end elevational view thereof, the other end being identical;

FIG. 4 is a side elevational view thereof, the other side being identical.

The cross hatched shading representing cloth repeats uniformly across the surface of the design.

Fig. 2.

Fig. 1.

Fig. 4.
